[57] CLAIM

The ornamental design for an icon for a display screen, as shown and described.

DESCRIPTION

FIG. 1 is a face view of an icon for a display screen showing my new design, the broken line drawing of a display screen is for illustrative purposes only and forms no part of the claimed design;

FIG. 2 is a face view thereof, the icon is shown separately for clarity of illustration.

1 Claim, 2 Drawing Sheets

FIG. 1

FIG. 2
